US00D806933S

(12) **United States Design Patent** (10) Patent No.: **US D806,933 S**
(45) Date of Patent: **** Jan. 2, 2018**

(54) **FLOATING SOLAR LIGHT**

(71) Applicant: **Compurobot Technology Company**,
Dongguan (CN)

(72) Inventor: **Wing-Tak Hui**, Hong Kong (CN)

(73) Assignee: **COMPUROBOT TECHNOLOGY CO.**,
Dongguan (CN)

(**) Term: **15 Years**

(21) Appl. No.: **29/573,240**

(22) Filed: **Aug. 3, 2016**

(51) LOC (11) Cl. **13-02**

(52) U.S. Cl.

USPC **D26/102**
